SYSTEM FOR CONVERTING MECHANICAL MOVEMENT INTO A RELATED NUMBER OF ELECTRICAL PULSES

Lee M. Griswold, Pasadena, Calif.

Application June 22, 1953, Serial No. 363,175

10 Claims. (Cl. 307—98)

The present invention relates to an electrical system which functions to produce a definite number of electrical pulses in accordance with the amount of movement of an element from one position to a second position.

In various electrical arrangements, which are commonly referred to in a generic sense as computers, pulse techniques are used to produce the desired results. In such arrangements, it is often desirable to represent the amount of movement of an element from one position to a second position in terms of a corresponding number of electrical pulses, where such movement may be either rectilinear, i. e., in a straight line, part of a circle, or along a helix. For that purpose, the following description is directed to means and techniques whereby these results may be achieved.

Briefly, the arrangements described herein which are termed converters since they serve to convert mechanical movement into electrical pulses, involve two conductors which are maintained at different electrical potentials, such conductors being arranged to be contacted by an element whose movement results in the development of a number of pulses, the exact number of such pulses being related to the degree of movement of such element.

It is, therefore, a general object of the present invention to provide means and techniques whereby the above indicated results may be achieved.

A specific object of the present invention is to provide means and techniques whereby these results may be achieved in a very simple manner.

Another specific object of the present invention is to provide means and techniques of this type which are useful in the development of a number of pulses in accordance with the total amount of movement of an element, either backwards or forwards or both backwards and forwards.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 shows certain details of a converter embodying features of the present invention and Figures 2 and 3 show certain details of two modifications of the converter illustrated in Figure 1.

The converter shown in Figure 1 includes a pair of interlaced but insulated spirally wound wires 10 and 11, the wire 10 being connected to the positive terminal of source 12 while the other wire 11 is connected to the negative terminal of source 12 through the resistance 14.

The wires 10, 11 may either be wound on a straight core 16 of insulating material, such core being of any desired cross-section, i. e., either round, circular, rectangular, square, polygonal, etc. Instead of such core 16 extending straight as shown in Figure 1, such core 16 may follow generally the arc of a circle or may lie on a portion of a spiral. In either case, the spirally wound interleaved or interlaced wires 10, 11 are arranged to be bridged by a contact element 20 to thereby close a circuit for the passage of current through the serially connected

2

battery 12 and load resistance 14. It is thus understood, that when the contact 20 is in the position illustrated in Figure 1, a current flow is produced through load resistance 14; and, that when the contact 20 engages only wire 11, or engages only wire 10, no current flows through the resistance 14. Thus, a continuous movement of the contact 20 results in an intermittent flow of current through the resistance 14, i. e., a series of current pulses flows through resistance 14 to develop a corresponding number of voltage pulses across the output terminals 22, 23.

The contact 20 may take different forms in that it may be a rolling contact, i. e., a roller as shown in Figure 1, which is biased into engagement with the wires 10, 11, or both wires 10 and 11, as the case may be, by a spring arm 15. 26. The upper end of the spring 26 is fastened, for example, to the element 28 which is movable in a straight line, either backwards or forwards, as represented by the arrows 30. For that purpose, suitable guideways (not shown) are provided between the stationary supporting element 32 and the movable element 28. The element 28 may be coupled to different members, whose movement is desired to be measured in terms of electrical pulses developed at the terminals 22, 23.

Although the electrical contact 20 is illustrated in the form of a roller, it is obvious that such contact 20 may take other forms; however, a roller is preferred since on wearing the roller remains round and is thus unlikely to bridge a number of turns as may be the case when a sliding contact is worn flat. For example, the contact 20 may be a sliding contact although a rolling contact is preferred. It is thus apparent, that the amount or degree of movement of the element 28 in Figure 1, either to the right or to the left, is represented by a corresponding number of voltage pulses developed at the terminals 22 and 23 with the exact number of such pulses being independent of the direction of movement of the element 28. In other words, the device may be considered to integrate all movements of the element 28, either to the right or to the left in Figure 1, or a combination of right and left movements of the element 28.

In the arrangement shown in Figure 2, the wires 10 and 11 are wound as shown in Figure 1, but the wire 11 is connected in a different manner with respect to the voltage source 112 and contact 20. It is assumed, as before, that the wires 10 and 11 have the same diameter. One end of wire 11 is connected to the negative terminal of source 12 through resistance 14, as in Figure 1, but the positive terminal of source 12 in Figure 2 is connected to the contact 20. Otherwise, the structure and operation of the arrangement illustrated in Figure 2 is identical, it being noted, however, that current flows through the resistance 14 only when the contact 20 in Figure 2 engages one of the convolutions of the wire 11 and that no current flows through the resistance 14 when the contact 20 is in engagement with the insulation 110.

In the arrangement illustrated in Figure 3, the bare wires 10, 11 are wound on the core 16 in the same manner as illustrated in Figure 1, but in such case, the contact 20 is connected to one output terminal 35, the other output terminal 36 being connected to the positive terminal of source 12. Thus, when the contact 20 is in engagement with a convolution of wire 11 alone, there is no voltage developed across the output terminals 35, 36; when the contact 20 engages a convolution of wire 10 alone, a voltage is developed across the output terminals 35, 36 which is equal in magnitude to the voltage of source 12; and, when the contact 20 bridges adjacent convolutions of the wires 10 and 11, there is likewise no voltage developed across the terminals 35, 36.

The arrangement shown in Figure 1 is considered to be most advantageous for the reason that no connection

is required to the moving contact, and further, such arrangement produces the most number of pulses (or highest resolution) per number of wires traversed.

Thus, devices are disclosed herein for use in converting mechanical position, movement, rate and change of rate into digital electrical pulses which indicate the same. The pulses which are developed may be directly recorded as numerals, Arabic or otherwise.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. In a converter of the character described, a pair of bare wires which are interlaced but insulated one from the other, a voltage source, an impedance, a movable contact, a serial circuit comprising one of said wires, said contact, said source, said impedance and the other of said pair of wires, said movable contact being engageable with different ones of said wires alone and to bridge the same alternatively, only one terminal of said source being connected to each of said wires, the other terminal of said source being connectible to a portion of either of said wires only through said contact.

2. In a converter of the character described, a pair of spirally wound elements, one of said elements being a bare electrical conductor and the other one of said elements including insulation, a movable contact engageable alternatively with said bare conductor, said insulation, and to bridge said insulation and said conductor, a voltage source, an impedance, said contact, voltage source, impedance and said bare conductor being serially connected, only one terminal of said source being connected to said conductor, the other terminal of said source being connectible to said conductor only through said contact, said contact being a switching element for alternately opening and closing a circuit through the serially connected contact, voltage source, impedance and said bare conductor.

3. In a converter of the character described, a pair of spirally wound bare wires, each insulated one from the other, a movable contact which is movable alternatively into engagement with one or the other of said wires or to bridge the same, an electrical source, an impedance, a series circuit comprising said source, said impedance, said one conductor and said other conductor, said contact being connected to one terminal of said source, and a pair of output terminals interposed between said one terminal and said contact.

4. A converting system for converting mechanical movement into related electrical pulses, each of substantially the same intensity comprising a voltage source having a first terminal and a second terminal, an impedance, a pair of spirally-wound interlaced bare wires, a movable contact member arranged to contact, in its movement, either one of said wires, or to bridge adjacent convolutions of both wires, said first terminal being connected through said impedance to one of said wires, said second terminal being connected to the other one of said wires, such contact when in position to bridge said adjacent convolutions being effective to produce a current flow through said source, said impedance, a portion of said two wires and said contact, and said contact when in position to contact either one of said two wires being in position to interrupt said current flow, and a pair of output terminals connected to opposite terminals of said impedance.

5. A converting system for converting mechanical movement into related electrical pulses, each of substantially the same intensity comprising a voltage source having a first terminal and a second terminal, an impedance, a pair of spirally-wound wires, one of said wires

being bare and the other being insulated, a movable contact member arranged to contact, in its movement, said one wire and then said other wire in succession, said first terminal being connected through said impedance to said one wire, said second terminal being connected to said movable contact, said contact when in position to engage said one wire being effective to produce a current flow through said source, said impedance, a portion of said one wire, and said contact, and said contact when in position to engage said other wire serving to interrupt said current flow, and a pair of output terminals connected to corresponding opposite terminals of said impedance.

6. A converting system for converting mechanical movement into related electrical pulses, each of substantially the same intensity comprising a voltage source having a first terminal and a second terminal, an impedance, a pair of spirally-wound interlaced bare wires, said first terminal being connected through said impedance to one of said wires, said second terminal being connected to the other one of said wires, a movable contact member arranged to contact, in succession, said one wire, then to bridge the convolutions between adjacent wires, and then to contact said other wire, a first output terminal connected to said movable contact, a second output terminal connected to said second terminal of said source, the voltage between said output terminals being relatively low when said contact engages said one wire, the voltage between said output terminals being relatively high when said contact bridges the convolutions between adjacent wires, and the voltage between said output terminals being relatively high when said contact engages said other wire.

7. A converting system for converting mechanical movement into related electrical pulses, each of substantially the same intensity comprising a voltage source, an impedance, a pair of spirally-wound wires, one of said wires being bare and the other one of said wires being insulated, a movable contact arranged to contact in succession said one wire and then said other wire, a series circuit including said source, said impedance and said contact to produce a current flow through said impedance only when said contact engages said one wire.

8. A converting system for converting mechanical movement into related electrical pulses, each of substantially the same intensity comprising a voltage source, an impedance, a spirally-wound wire, a movable contact arranged to engage, in its movement, individual convolutions of said wires, a series circuit including said source, said impedance, a portion of one of said wires, and said contact, said source having only one of its terminals connected to said one wire, the other terminal of said source being connectible to said wire only through said contact.

9. A system as set forth in claim 7 in which a second wire is spirally-wound in interlaced manner with said spirally-wound wire and said contact is arranged to engage spaced convolutions of said second wire in movement of the contact, said other terminal of said source being connected to said second wire, and said contact being arranged to bridge the spacing between the first-mentioned wire and said second wire.

10. A system as set forth in claim 7 in which a second insulated wire is spirally-wound in interlaced manner with said spirally-wound wire and said contact is arranged to engage spaced convolutions of said second insulated wire in movement of the contact, said insulated wire serving as an insulated spacer between adjacent convolutions of the first-mentioned wire.
